UNITED STATES PATENT OFFICE.

RICHARD E. SCHLETTER, OF ELKINS PARK, PENNSYLVANIA, ASSIGNOR TO SCHLETTER & ZANDER, INC., OF PHILADELPHIA, PENNSYLVANIA, A CORPORATION OF PENNSYLVANIA.

LADY'S HOSIERY.

Application filed November 26, 1924. Serial No. 752,283.

This invention relates to ladies' hosiery and has more especial relation to the manner of forming the leg portion thereof immediately below the welt.

5 Ladies' hosiery is subjected to considerable strain at the welt where engaged, in use, by supporters, with the result, that, at the place or places of concentration of strain, a thread or threads give way to cause what is termed 10 in the trade, "a run". This results in spoiling the appearance and in a short time the usefulness of the stocking. Attempts have been made by manufacturers to prevent the deleterious effect of so called "runs" with 15 varying success. Reinforced areas have been supplied in the welt to accommodate supporter attachment, but these areas are so small, that except in a restricted area they fail to prevent "runs".

20 The leading object of the present invention is to provide an improved type of hosiery in which "runs" are eliminated below the welt by introducing in the stocking leg, immediately juxtaposed below the welt, 25 and extending entirely around the upper leg portion, a plaited or reinforced area, so that any "run" occurring in the welt is precluded from advancing beyond said plaited or reinforced area. Another object is to so fashion 30 the plaited or reinforced area that a good appearance is presented in order to render the hosiery acceptable to a critical purchasing public.

With these and other objects in view the 35 invention consists of the novel construction hereinafter described and finally claimed.

The nature, characteristic features and scope of the invention will be more fully understood from the following description 40 taken in connection with the accompanying drawings forming part hereof, and in which:

Fig. 1, is a view in elevation of a stocking embodying the invention.

45 Fig. 2, is a view in section taken upon the line 2—2 of Fig. 1, and

Fig. 3, is a view of the welt and upper leg portion of a stocking embodying the invention and illustrating the same prior to seam- 50 ing up of the back thereof.

For the purpose of illustrating my invention I have shown in the accompanying drawings one form thereof which is at pres-

ent preferred by me, since the same has been found in practice to give satisfactory and 55 reliable results, although it is to be understood that the various instrumentalities of which my invention consists can be variously arranged and organized and that my invention is not limited to the precise arrangement and organization of the instrumentalities 60 as herein shown and described.

In the formation of my improved stocking the welt 10 may be of the same material or different material than the leg portion. That 65 is the welt may be of, for instance, silk and knitted simultaneously with the leg portion, or the welt may be of, for instance, cotton and attached after leg 11, foot 12, and toe 13 formation as is well understood in the art 70 and forms no part of the present invention. Irrespective of the material employed, at the place of juncture of the welt with the stocking leg, designated 14 in the drawings, I introduce into the stocking web an additional 75 thread, either by means of plaiting or by means of reinforcing so that from one side 15 to the opposite side 16 of the stocking web, see Fig. 3, I provide immediately below the welt 10, from juncture 14, a continuous 80 area 17 containing an additional thread. The essential feature of the present invention resides in the provision of this plaited or reinforced area 17 regardless of its shape or design so long as it extends entirely across 85 the stocking leg at its top and immediately juxtaposed to the welt. However, for illustrative purposes only, I have shown in the drawings a number (two or more) of depending, pointed areas 18 formed upon zig- 90 zag lines as is well known in the art. Such configuration adds to the ornamental appearance of the stocking, usually of fine silk chiffon and tends to increase the sale of a stocking having the characteristics of a 95 "run" preventing area 17. Obviously, however, other designs and configurates in which are embodied a continuous "run"-preventing area immediately below the welt may be employed without departing from the spirit of 100 the present invention. It is thus apparent, that, if for any cause, as for example, strain exerted by a supporter, a "run" occurs in the welt 10, such "run" cannot pass below the lowermost portion of the continuous area 105 17 or below the boundaries of the orna-

mental figures 18, thus effectually maintaining a "run" within a restricted area to preclude its marring the appearance and ultimate usefulness of the stocking leg. The 5 above described stocking is fabricated upon a flat knitting machine and the web is seamed at the back as at 19.

It will now be apparent that I have devised a novel and useful construction which 10 embodies the features of advantage enumerated as desirable in the statement of the invention and the above description and while I have in the present instance shown and described the preferred embodiment thereof 15 which has been found in practice to give sat-

isfactory and reliable results, it is to be understood that the same is susceptible of modification in various particulars without departing from the spirit or scope of the invention or sacrificing any of its advantages. 20

What I claim is:

A full-fashioned stocking having immediately below the welt a continuous series of depending V-shaped reinforced areas of 25 yarn added to the body yarn, said reinforced areas tapering step-by-step to provide anti-run margins for said reinforced areas.

In testimony whereof, I have hereunto signed my name.

RICHARD E. SCHLETTER.
